FIG. 1

FIG. 5

FIG. 2

FIG. 3

FIG. 4

FIG. 6

FIG. 7

FIG. 8

FIG. 1 is a left side elevational view of a security case for a calculator showing my new design;

FIG. 2 is a left end view thereof;

FIG. 3 is a right end view thereof;

FIG. 4 is a right side elevational view thereof;

FIG. 5 is a top plan view thereof;

FIG. 6 is a bottom plan view thereof;

FIG. 7 is a front perspective view thereof;

FIG. 8 is a rear perspective view thereof.

The broken line disclosure of a calculator in FIG. 8 is for illustrative purposes only and forms no part of the claimed design. The cord is shown fragmentarily in FIGS. 1, 3, 4, 5, 6 and 8 for ease of illustration.

I claim:

The ornamental design for a security case for a calculator, as shown and described.
